(57) **CLAIM**

The ornamental design for an electric washing machine, as shown and described.

DESCRIPTION

FIG. 1 is a front perspective view of the electric washing machine showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a reference view showing the state of use that the display part of the claimed design has been operated; and, FIG. 9 is a reference view showing the state of use that the claimed design has been used in combination with another electric washing machine.

The broken lines depict portions of the electric washing machine that form no part of the claimed design. The portions of FIG. 9 drawn in broken lines show environmental structure only and form no part of the claimed design.
